UNITED STATES PATENT OFFICE.

ALMON D. SIEWERT, OF PASADENA, CALIFORNIA.

TOOTH-PASTE DISPENSER.

Application filed July 7, 1927. Serial No. 203,913.

This invention relates to improvements in tooth-paste dispensers and more particularly to a container for dentifrice in paste form including means for discharging small quantities therefrom as needed.

The object of the invention is to provide a container calculated to afford the manufacturer a practical and inexpensive package for tooth paste and the consumer with a convenient means for dispensing the same.

A further object of the invention is to provide a combined dispensing container for tooth paste and a holder or case of a tooth brush.

15 A preferred embodiment of the invention is disclosed in the accompanying drawings, in which

Figure 1 is a perspective view of the container without brush holder, with a section 20 removed to show the construction.

Figure 2 is a top plan view of the container with cap removed.

Figure 3 is a perspective view of the rotative operating member.

25 Figure 4 is a perspective cut-away view of a modification of the container with provision for carrying a tooth brush.

Figure 5 is a perspective view of the inner tube of the modified container with compartments for a tooth brush and an antiseptic substance.

Figure 6 is a view in cross section taken on line 6—6 of Figure 4.

Figure 7 is a perspective cut-away section 35 of a cap for the modified container; and

Figure 8 is a view in cross section through the cap as taken on line 8—8 of Figure 7.

The form of container and dispenser shown in Figures 1, 2 and 3, comprises in general a 40 cylindric body 1 and a shallow cover or cap 2 fitting over the top of the body. The body preferably consists of a metal tube 3 of a double thickness of relatively thin metal, the walls of the tube being sufficiently stiff to prevent the body from being crushed or dented. The upper end of the tube is permanently 45 closed by a cap 4 fixed over the edge of the tube and providing a downwardly facing shoulder 4^a about the edge of the body. Near the periphery of the cap is an upstanding curved boss 5 having a slot 5^a therein through which the paste is discharged. The bottom or lower end of the tube 3 is open and fitting snugly therein is a disc 6 which in the filled 50 condition of the tube forms a movable bottom wall for the contents of the tube. The

center of this disc is provided with a threaded opening to receive the end of a rod 7 extending axially of the tube and has a helical thread 7^a throughout its length. The upper 60 end of the rod projects through the cap 4 and terminates above the same in a square end 7^b.

Surrounding the tube adjacent its upper end is a split collar 8 having an integral radial arm 9 extending inwardly to its center from one point of its periphery, the arm being bent so as to provide an inverted U-shaped portion or hump 9^a in radial alignment with the boss 5 at the upper end of the body 1 and adapted to permit the arm to clear or pass over the boss when the former is rotated in the act of dispensing the paste from the tube. Inwardly from the closure portion 9^a extends a radial finger 9^b lying flatwise against the 70 top of the body, and having a square opening through which the square end 7^b of the screw rod 7 extends. The split collar 8 surrounds the tube 3 just below the shoulder 4^a formed by the cap 4 and with sufficient tightness to 75 be frictionally held against free rotation. Moreover, it is held from endwise displacement by the shoulder 4^a of the cap and the arm 9 bearing against the top of the cap.

Assuming that the tube is filled with tooth 80 paste with the disc 6 at the bottom, the rotation of the rod 7 by turning the collar 8 in a clockwise direction, as shown in Figure 1, causes the disc 6 to travel upwardly on the rod thus forcing the paste through the slot 90 5^a in the amount required for one application. The closure cap 2 is removed while the container is in use, but otherwise fits over the end with a snug friction fit.

The form of container shown in Figures 4 95 to 8, inclusive, is similar in its general construction to the one already described. In this instance, the body 10 is of a double thickness of metal with an outer tube 10^a surrounding a separate inner tube 10^b carried over the upper end to form a top wall 11 in which the slotted boss 11^a as before is formed. This form of container has a bottom wall 12 fitted over the lower end of the tube 10 and a flanged ring 13 fitted around the upper end and forming a shoulder for the same arrangement of rotative collar threaded rod and disc as already described. In this instance, however, the disc is shaped to the cross sectional contour of the body, which is not circular owing 105 to the provision of a tooth brush compartment.

Figure 5 shows the inner tube removed and a portion of its cylindric wall concave inwardly throughout its length to form a recess of sufficient size to provide an endwise opening cavity 14 for the handle of a tooth brush when the inner and outer tubes are assembled. In addition to the handle cavity, a smaller cavity 15 opening through the top wall 11 of the tube is formed by a partition wall 16 (Figure 6) extending from the recessed portion of the tube 10^a to a point a short distance beyond, thus forming a triangularly shaped cavity which is filled with a suitable antiseptic substance in solid form.

Owing to the provision for carrying a tooth brush, a closure cap 17 of somewhat greater length is used in order to provide sufficient space for the projecting head of the brush. If desired, and in place of the antiseptic compartment 15 in the body of the container, the space within the closure cap can be filled with a solid antiseptic 18 with a recess 18^a formed to receive the head of the brush.

I claim as my invention:

1. A dispenser for the purpose described, comprising a container having a discharge

opening at one end and consisting of an outer and inner cylindric wall, said inner wall having a longitudinal recess forming a cavity between the same and said outer wall, a disc slidably mounted in said container, a rotative rod having threaded engagement with said disc, and means for rotating said rod to move said disc.

2. A dispenser for the purpose described, comprising a cylindric container closed at one end and having a discharge opening at its opposite end, a disc slidably mounted in said container below the contents thereof, a rod extending axially of said container and through said disc, said rod being provided with a helical thread engaging said disc, a collar surrounding said container adjacent the discharge end thereof and frictionally held against free rotation, and a radial arm connecting said collar with the adjacent end of said rod and adapted to form a closure for said discharge opening.

Signed at Pasadena this 1st day of July, 1927.

ALMON D. SIEWERT.
